(57) **CLAIM**

The ornamental design for an inflatable device, as shown and described.

DESCRIPTION

FIG. 1 is a top, front, right-side perspective view of an inflatable device;

FIG. 2 is a back, bottom, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The longer dashed broken lines depict portions of the inflatable device that form no part of the claimed design. The shorter dashed broken lines depict a fringe trim material of the inflatable device that forms no part of the claimed design.

1 Claim, 8 Drawing Sheets

FIG. 2

FIG. 3

FIG. 4

FIG. 5

FIG. 6

FIG. 7
